Patented May 28, 1918.

UNITED STATES PATENT OFFICE.

ROBERT HENRY ELSEY, OF PRESCOTT, ARIZONA.

PUMP.

1,267,856.

Specification of Letters Patent.

Patented May 28, 1918.

Application filed March 23, 1917. Serial No. 156,885.

To all whom it may concern:

Be it known that I, ROBERT HENRY ELSEY, a citizen of the United States, residing at Prescott, in the county of Yavapai and State 5 of Arizona, have invented new and useful Improvements in Pumps, of which the following is a specification.

This invention relates to a pump and particularly pertains to a deep well pump. 10 It is the principal object of this invention to provide a deep well pump which is adapted to work under a load during the up and down strokes of its plunger and which will rapidly and easily elevate a column of water 15 from a well.

Another object of this invention is to provide a deep well pump which is formed of few and easily constructed parts.

Another object of this invention is to provide a deep well pump which does not require the use of expensive and complicated valves but operates effectively with valves of simple construction formed of parts which may be readily interchanged at small 25 expense.

It is a further object of this invention to provide a deep well pump mechanism which actuates its valves automatically and in synchronism with the reciprocation of the plunger. 30

Other objects will appear hereinafter.

The invention is illustrated, by way of example, in the accompanying drawings in which:

Figure 1 is a view in vertical section illustrating the pump ready for operation.

Fig. 2 is a view in transverse section as seen on the line 2—2 of Fig. 1 viewed in the direction of the arrows, and particularly discloses the construction of the plunger valve. 40

Fig. 3 is a view in transverse section as seen on the line 3—3 of Fig. 1 viewed in the direction of the arrows, and particularly discloses the construction of the pump cylinder valve. 45

Referring more particularly to the drawings, 10 indicates a pump cylinder. This cylinder is preferably formed in two parts bolted together by bolts 11, 12, 13 and 14.

50 A bolting flange 15 is formed around the lower end of the cylinder and is adapted to receive bolts 16 which secure a pipe fitting 17. The fitting 17 is threaded in order to connect with the well casing 18. The cylinder 10 is formed with a straight bore 19 along which a hollow pump plunger 20 is

adapted to reciprocate. This plunger is cylindrical in shape and is surrounded by a stuffing box 21 which prevents leakage of the water from the cylinder and around the 60 plunger.

The pump plunger is adapted to be reciprocated by a pump rod 22 which is connected with a suitable pumping mechanism. The reciprocation of this plunger acts to operate 65 a plunger valve 23 and a cylinder valve 24. These valves are similar in construction and operate alternately to permit water to be drawn into the cylinder upon the up stroke of the plunger and to thereafter permit this 70 volume of water to pass into the plunger upon the down stroke thereof. The plunger valve 23 is formed of a lower valve seat disk 25 which is held over the end of the plunger by means of screws 26. A series of openings 75 27 are formed through this disk and are adapted to permit water to flow into the chamber 28 which extends the length of the plunger and is incorporated therein. Upon the up stroke of the plunger a second disk 80 29 rests against the disk 25 and closes the openings therein. This disk is mounted within a counter-bore 30 formed at the end of the plunger and is formed with a central bore 31 through which the water passes 85 when the plunger is on its down stroke.

The cylinder valve 24 is mounted at the lower end of the cylinder and is composed of a large valve seat disk 32 formed with a series of openings 33, and a small valve disk 90 34 formed with a central opening 35. This second-named disk is loosely mounted within a counter-bore 36 formed at the end of the cylinder bore. The disk 32 is removably held in position by the pipe fitting 17 which 95 is secured to the end of the cylinder by a bolt 16, as previously stated.

In order to carry the water, lifted by the pump, away from the plunger, a pipe 37 is mounted at the upper end of the plunger 100 and is provided with a universal pipe union 38 which in turn connects with a check-valve 39. It will be understood that the pipe leading from the valve 39 is the main supply pipe and that it may be extended any length 105 desired.

In operation, the cylinder 10 and the pipe fitting 17 are vertically mounted upon the end of the well casing 18. The pump rod 22 is then connected with a suitable pumping mechanism and the plunger caused to reciprocate within the cylinder. Upon the

upstroke of the plunger the valve disk 29 will be held firmly against the valve disk 25 upon which it is supported. This will cause the plunger to produce suction within the 5 pump cylinder and will raise the disk 34 from the disk 32. When these disks are separated, water will be drawn in through the openings 33 in disk 32 and the opening 35 in disk 34. This action will continue 10 during the upstroke of the plunger. When the plunger starts upon its down stroke, the column of water within the cylinder will be trapped, due to the pressure of the water and its weight upon the disk 34. This disk 15 will immediately be lowered against the disk 32 and will cause the openings 33 and 35 to be closed. As the plunger continues upon its down stroke, the disk 29 will be raised in relation to the disk 25 and the water within 20 the cylinder will pass through openings 27 and 31 to the interior of the plunger. It will be understood that this plunger is already filled with water drawn in on the previous down stroke and the variation in 25 the effective surface pressures of the column of water within the plunger and the column of water beneath the plunger will cause the water within the plunger to be ejected therefrom through the pipe 37.

30 It will be understood that the stroke of the pump plunger may be varied to suit the various conditions under which the pump is adapted to work and that the device may be used equally well for drawing water from 35 mine shafts.

It will thus be seen that the pump here disclosed is composed of few operative parts, all of which are simple in their construction, may be readily formed, and act effectively 40 in their pumping operation.

While I have shown the preferred construction of my pump as now known to me, it will be understood that various changes in the combination, construction, and arrangement of parts may be made by those skilled in the art without departing from the spirit of my invention.

I claim:

50 1. In a pump, a pump cylinder formed in two parts, said parts meeting on diametrical longitudinal lines and said parts being rig-

idly bolted together, a bolting coupling flange formed integral around the lower end of the cylinder, a tapered fitting secured to the bolting flange and having an internal 55 thread in its lower reduced end, a pipe in the internal thread; there being a counter-bored chamber at the lower end of the cylinder and upper end of the fitting; a perforated valve seat disk rigidly mounted in the 60 counter-bored chamber, and a floating valve disk loosely mounted in the counter-bored chamber upon the rigid disk and having perforations mismatching the perforations in the rigid disk so as to form an up flowing 65 check-valve; the area of the check-valve capacity being equal to the capacity of the pipe.

2. In a pump, a pump cylinder, a pump plunger slidably mounted in the cylinder 70 and having a counter-bored chamber in its lower end, a valve seat disk rigidly mounted in said chamber, and a second valve disk loosely mounted in said chamber upon the rigid valve seat disk; there being mismatching 75 perforations through said rigid valve seat disk and said loose valve disk so that liquid may flow upwardly into the plunger and may not flow downwardly.

3. In a pump, a pump cylinder formed in 80 two pieces meeting on diametrical and longitudinal lines, bolts securing the two pieces rigidly together, a pump plunger fitting closely in the pump cylinder, means forming a stuffing box around the pump plunger, a 85 reducing fitting connected to the lower end of the pump cylinder, a pipe connected to the reducing fitting; there being a counter-bored chamber at the lower end of the pump cylinder and a counter-bored chamber at the 90 lower end of the pump plunger; valve seat disks rigidly mounted in said counter-bored chambers, and valve disks loosely mounted in said counter-bored chambers above the rigid disks; there being mismatching perforations through each rigid disk and its co-operating loose disk so as to form up flowing 95 check-valves equal in capacity to the flow through the pipe.

In testimony whereof I have signed my 100 name to this specification.

ROBERT HENRY ELSEY.
